FIG. 3.

FIG. 4.

FIG. 5.

Inventor
J. Tymkow

J. A. Dugay, Jr.
Attorney.

UNITED STATES PATENT OFFICE.

JOSEPH TYMKOW, OF ARDROSSAN, ALBERTA, CANADA, ASSIGNOR OF ONE-FOURTH TO
MIKE SENYK AND ONE-FOURTH TO PETER JACOBS, BOTH OF ARDROSSAN, AL-
BERTA, CANADA.

MECHANICAL ROUNABOUT.

Application filed June 18, 1923. Serial No. 646,061.

To all whom it may concern:

Be it known that I, JOSEPH TYMKOW, a citizen of Poland, residing at Ardrossan, in the Province of Alberta and Dominion of Canada, have invented certain new and useful Improvements in Mechanical Roundabouts, of which the following is a specification.

This invention relates to new and useful improvements in mechanical toys of the roundabout type.

An important object of the invention is to provide a mechanical toy which is intended to furnish amusement and entertainment to persons watching the operation of the same.

A further object of the invention is to provide an improved form of mechanical toy which somewhat resembles the operation of a ferris wheel, but possesses means for varying the movement of the various cars in respect to each other during their travel in an arcuate path.

Other objects and advantages of the invention will be apparent during the course of the following description.

In the accompanying drawings forming a part of this specification and in which like numerals are employed to designate like parts throughout the same,

Figure 1 is a side elevational view of the mechanical toy embodying this invention,

Figure 2 is a plan view of a stationary base adapted for carrying a portion of the mechanism and an adjustable base adapted for carrying the remaining portion of the mechanism, the supporting struts or legs being shown in horizontal cross-section, taken on line II—II of Fig. 1,

Figure 3 is an end elevational view of the mechanical toy shown in Fig. 1,

Figure 4 is a fragmentary sectional view taken on line IV—IV of Fig. 1, and

Figure 5 is a sectional view taken on line V—V of Fig. 1.

In the drawings, wherein for the purpose of illustration is shown a preferred embodiment of this invention, the numeral 5 designates a plate or base constructed from any suitable material, such as metal or the like, and is formed integrally with a substantially rectangularly-shaped box formation 6 which is positioned laterally of the said plate or base 5 and extends longitudinally of the same. Formed integrally with the

base or plate 5 are a series of struts or legs 7 which are connected at their upper ends to form a pair of spaced split bearings 8 which are adapted for rotatably supporting a horizontal shaft 9 which is keyed to a hub 10 that carries radially extending circular spokes 11 having connected to their outer ends a circular band 12.

Slidably mounted within the rectangularly-shaped box-like structure 6 is a block or base 13 which is partially supported upon the floor 6^a of the said box-like structure 6 and is provided with a longitudinally extending internally threaded bore 14 which is adapted for operatively engaging the rotatable feed screw 15 which is journaled in the opposite ends 16 of the said box-like structure 6 and is provided with spaced collar elements 17 that are adapted for preventing longitudinal movement of the said feed screw in respect to the box-like structure 6. Formed integrally with the block or base 13 are a series of struts or legs 18 that converge upwardly for the purpose of forming a split bearing member 19 at their upper ends which is adapted for rotatably carrying the horizontal stub shaft 20. Suitably keyed to or rotatably mounted on this horizontal stub shaft 20 is a hub 21 that is provided with a series of rectangularly-shaped recesses or pockets 22 formed in its peripheral face for the purpose of receiving the reversely bent spokes 23 pivotally secured thereto by means of the fulcrum pins 24, as best shown in Fig. 4. The outer ends of these spokes 24 are each provided with an aperture that receives a small pin or shaft 25 rotatably therein which is formed integrally with a tubular block member 26 that slidably encircles one of the said radial spokes 11, as best shown in Fig. 4. Directly opposite this pin or shaft 25 is a second pin or shaft 27 that is formed integrally with the tubular block 26 and is adapted for rotatably connecting a chair or car 28 to the said block 26. There are further provided washers or spacing collars 29 that encircle the said pins or shafts 25 and 27 and are positioned between the outer ends of the spoke 23 and the block 26 and between the said block and the car or chair 28 for the purpose of better enabling relative movement to occur between the said spoke, block, and chair.

For the purpose of rotating the shaft 9,

there is provided a pulley 30 suitably keyed to the outer end of the same and to which power may be delivered from any suitable source, such as a small electric motor, a small steam engine, or a suitable spring motor.

The operation of the device is as follows:—

10 The provision of the adjustable block or base 13 is for the purpose of shifting the horizontal stub axle 20 laterally in either direction from the horizontal shaft 9 and its range of movement is from substantially the position shown in Fig. 1 to a similar position at the left of the said horizontal shaft 9.

Considering first that the horizontal stub shaft 20 is directly in axial alinement with the horizontal shaft 9. It will be seen that 20 by delivering power to the pulley 30, the horizontal shaft 9 will be caused to rotate and will thereby rotate the radial spokes 11 and band 12. Due to the fact that the tubular blocks 26 with their pivotally supported chairs or cars 28 are directly connected to the radial spokes 11, the rotation of these spokes will cause the blocks 26 and cars or chairs 28 to travel in an arcuate path around the stub shaft 20. During this 30 rotation of the various elements, the cars or chairs 28 will be retained at all times at equal distances apart. When it is desired to somewhat vary the movement of the cars or chairs 28 in respect to the radial spokes 11 and band 12, the feeding screw 16 is located in either direction for causing the block or base 13 to travel along the same thereby shifting the horizontal stub shaft 20 laterally in either direction from the said 40 horizontal shaft 9. It will now be apparent that during the rotation of the shaft 9 with its rigidly connected spokes 11 and band 12, the blocks 26 will be caused to reciprocate upon the said spokes 11 as well as to travel 45 in an arcuate path in respect to the stub shaft 20. Similar movement will naturally be transmitted to the chairs or cars 28 and will therefore furnish an amusing and entertaining sight for persons watching the 50 operation of the same. It will be seen by inspecting Fig. 1 of the drawing, that with the stub shaft 20 positioned to the right of the said horizontal shaft 9 that the cars or chairs 28 will be positioned a greater distance apart when they are traveling in an arcuate path to the right of the said shaft 9 than the chairs or cars 28 while traveling in an arcuate path to the left of the said shaft 9.

55 It is to be understood that I do not desire to limit myself to employing this construction as a toy for it may as suitably be employed in an amusement park as a mechanical roundabout for carrying human beings.

60 It is to be understood that the form of

this invention herewith shown and described is to be taken as the preferred example of the same, and that various changes in the shape, size, and arrangement of parts may be resorted to without departing from the 70 spirit of the invention or the scope of the subjoined claims.

Having thus described the invention, I claim:—

1. In a device of the class described, a 75 base, a shaft rotatably supported above said base, a spoked wheel keyed to said shaft; a second base, a stub shaft rotatably supported thereabove, a hub mounted on the stub shaft, radial spokes secured to said hub, blocks pivotally connected to said spokes encircling the spokes of said wheel, a car 80 rotatably connected to each block, and means for connecting the first mentioned rotatable shaft with a source of power for 85 driving the same to cause said cars to travel in an arcuate path.

2. In a device of the class described, a 90 base, a shaft rotatably supported thereabove, a spoked wheel keyed to said shaft; a second base adjustably associated with the first base, a stub shaft rotatably supported above the second base, a hub mounted on the stub shaft, radial spokes pivotally connected to said hub, a block rotatably connected to 95 each radial spoke encircling one of the spokes of said wheel, a car rotatably connected to each block, and means for connecting the first mentioned rotatable shaft with a source of power for driving the same 100 to cause said cars to travel in an arcuate path.

3. In a device of the class described, a 105 base, a shaft rotatably supported above said base, a spoked wheel keyed to said shaft; a second base, a stub shaft rotatably supported thereabove, a hub mounted on said stub shaft, radial spokes pivotally connected to said hub, a block rotatably connected to each spoke slidably engaging one of the 110 spokes of said wheel, a car rotatably connected to each block, means for connecting the first mentioned rotatable shaft with a source of power for driving said wheel to cause said cars to travel in an arcuate path, 115 and means for moving the second mentioned base in respect to the first for causing the blocks to reciprocate upon the spokes of said wheel during the rotation of the latter.

4. In a device of the class described, a 120 base, a shaft rotatably supported above said base, a spoked wheel keyed to said shaft; a second base mounted in said base, a box-like structure secured to said base, a 125 second base mounted in said box-like structure and adapted for reciprocating within the same, a stub shaft rotatably supported above the second base, a hub mounted on the stub shaft, radial spokes pivotally connected to said hub, a block rotatably connected to each spoke slidably engaging one of the 130

spokes of said wheel, a car rotatably connected to each block, means for connecting the first mentioned rotatable shaft with a source of power for driving said wheel to cause said cars to travel in an arcuate path, and means for moving the second mentioned base within said box-like structure for causing the stub shaft to be moved laterally out of axial alinement with the first mentioned shaft for causing the blocks to reciprocate upon the spokes of said wheel during the rotation of the latter.

5. In a device of the class described, a base, a shaft rotatably supported above said base, a spoked wheel keyed to said shaft; a box-like structure formed integrally with said base, a second base mounted in said box-like structure and adapted for reciprocating within the same, a stub shaft rotat-

ably supported above the second base, a hub 20 mounted on said stub shaft, radial spokes pivotally connected to said hub, a block rotatably connected to each spoke slidably engaging one of the spokes of said wheel, a car rotatably connected to each block, means 25 for connecting the first mentioned rotatable shaft with a source of power for driving said wheel to cause said cars to travel in an arcuate path, and means for moving the second mentioned base in respect to the first 30 for causing the stub shaft to be moved laterally out of axial alinement with the first mentioned rotatable shaft for causing the blocks to reciprocate upon the spokes of said wheel during the rotation of the same. 35

In testimony whereof I affix my signature.

JOSEPH TYMKOW.
